(Continued)*Primary Examiner* — Charles Hanson(74) *Attorney, Agent, or Firm* — Hanley, Flight and Zimmerman, LLC(57) **CLAIM**

The ornamental design for an ambulation aid, as shown and described.

DESCRIPTION

FIG. 1 is an isometric view of an ambulation aid.

FIG. 2 is a front view of the ambulation aid.

FIG. 3 is a rear view of the ambulation aid.

FIG. 4 is a first side view of the ambulation aid.

FIG. 5 is a second side view of the ambulation aid.

FIG. 6 is a top view of the ambulation aid.

FIG. 7 is a bottom view of the ambulation aid.

FIG. 8 is an isometric view of the ambulation aid; and,

FIG. 9 is a rear isometric view of the ambulation aid.

The features shown in broken lines form no part of the claimed design.
